UNITED STATES PATENT OFFICE.

WILLIAM M. GREENLEE, OF PITTSBURG, PENNSYLVANIA.

TRUSS.

SPECIFICATION forming part of Letters Patent No. 451,817, dated May 5, 1891.

Application filed March 17, 1891. Serial No. 385,373. (No model.)

To all whom it may concern:

Be it known that I, WILLIAM M. GREENLEE, of Pittsburgh, in the county of Allegheny and State of Pennsylvania, have invented a new 5 and useful Improvement in Trusses, of which the following is a full, clear, and exact description.

The object of my invention is to provide a comfortable effective truss for hernia, by which 10 the defects of prior trusses are overcome.

It is illustrated in the accompanying drawings, in which—

Figure 1 shows the truss applied to the human form. Fig. 2 shows the truss in vertical 15 section and on a larger scale.

My improved truss comprises a belt *a*, which is worn around the abdomen of the ruptured person and is attached to a plate *b*, carrying pads *b'*, which, with the plate, may be made of 20 hard rubber or any other suitable material. There are also straps *c*, which are attached to the rear of the belt, and are provided with pads *d* and with loops, hooks, or other attachments by which their ends may be secured to 25 the front of the belt. Said pads are flexible, as hereinafter explained, and are tapering in form, decreasing in thickness downwardly, being thick at a place immediately below the lower edge of the plate *b*, so that they may 30 supplement the action of the hard pads *b'*.

The rear attachment of the straps *c* to the belt is preferably by means of buckles *e*, which enable the length of the straps to be adjusted.

When the truss is worn, the belt *a* is placed 35 around the abdomen and secured to the truss-plate *b*. The straps are brought between the

legs from the place of attachment at the middle of the rear of the belt, and are attached to the truss-plate in front of the belt, and when thus adjusted the pads *d* fit at the sides 40 of the privates, extending back of the same, and as the straps *c* extend to the middle of the back the pads are caused to press inwardly and upwardly at the sides of the scrotum, and thus retain the rupture in place. 45 Where there is but a single rupture, only one of these pads may be used. It will be found that the truss, when constructed and worn in this manner, is of the greatest comfort and efficiency, so much so that the ruptured person may without danger perform his ordinary work, even if it be of arduous nature. The pads *d* are preferably made of stuffed leather pouches, since these are soft and do not chafe 50 or inconvenience the wearer.

55 I claim—

In a truss, the combination of a plate *b*, having hard pads *b'*, an abdomen-encircling belt attached to the plate, and flexible stuffed pads *d*, attached to the plate and decreasing 60 in thickness downwardly, said pads being adapted to extend to the rear of the scrotum on both sides thereof and having straps extending to the back of the belt at the middle part thereof, substantially as and for the purposes described.

In testimony whereof I have hereunto set my hand this 13th day of March, A. D. 1891.

WILLIAM M. GREENLEE.
